DESIGN FOR A GAME BOARD

Clifford Egerton, Kew Gardens, N. Y.

Application September 25, 1939, Serial No. 87,375

Term of patent 3½ years

To all whom it may concern:

Be it known that I, Clifford Egerton, a citizen of the United States of America, residing at Kew Gardens, L. I., county of Queens and State of New York, have invented a new, original, and ornamental Design for a Game Board, of which the following is a specification, reference being had to the accompanying drawing, forming part thereof.

I claim:

The ornamental design for a game board, as shown.

CLIFFORD EGERTON.
